CALVIN R. WAID, OF BIRMINGHAM, ALABAMA

GRATE BAR

Application filed December 6, 1928. Serial No. 324,098.

My invention relates to grate bars of the type in which a rocking assembly bar is provided and adapted to receive astride it a plurality of independently removable grate segments, each comprising a base adapted to straddle the assembly bar and a fire head preferably integral with such base.

Grates of the character above described, are generally denominated interchangeable grates, and it is of especial moment that the grate segments should be standard and therefore interchangeable and that they should be of such type as to be readily removable vertically without disturbing the assembly bar, and that they should be associated with means which will suitably space and effectually brace their fire heads.

My present invention embodies all of the advantages above described and in addition thereto provides grate units which comprise a single fire head and base, cast integral, with the fire head composed of a zig-zag element which crosses the assembly bar at an acute angle to its long axis, said fire heads having at their ends lateral bosses which abut, thus spacing and bracing their free ends.

Another feature of my invention relates to the arrangement for the spacing bosses disposed on opposite sides of the saddle, these bosses being arranged with downwardly sloping convex upper surfaces emerging symmetrically from opposite sides of the fire head near its base, both sides converging towards the center line of the assembly bar and terminating in vertical faces lying in planes at right angles to said axis. These abutting shoulders thus provided engage throughout the length of the assembly bar and serve to hold the segments in correct operating position.

A further feature of my invention resides in casting the saddle base so that it will take a bearing on the top edge of the assembly bar and will, by virtue of the presence of off-sets and tapering portions have only a bottom bearing on each side of the assembly bar, whereby the base casting is shaped to stand clear of the assembly bar except at its top and bottom points of contact, making it practi-

cally unnecessary to machine the saddle portion to remove small irregularities.

More particularly my invention comprises a grate segment casting comprising a body portion which is thin, which tapers in thickness downwardly from the top of the fire head to its bottom edge, and which increases in width from top to bottom as it approaches its central portion. The thin body being shaped to present zig-zag fire head of symmetrical and preferably uniform conformation with its depending center portion thickened sufficiently to provide a saddle having parallel vertical faces adapted by engaging corresponding faces of adjacent segment to serve as spacers.

My invention further contemplates cutting away the intermediate portions of the side abutment faces on the segment saddles to reduce the necessity for grinding and machine work in finishing the castings.

A further feature of my invention lies in arranging the upper portion of the fire head including the end abutments in a plane above the base portion of the fire head from which the saddle depends, thereby permitting the base portion of the saddle to be maintained as a standard and the upper portion forming the fire head to be cast with various modifications, according to the duty required, which can be accomplished by sectional patterns having interchangeable top portions for forming the variable upper portion of the fire head. By this arrangement, and at a greatly reduced expense for patterns, a variety of grate segment castings can be had for all types of fire boxes.

My invention also contemplates giving a zig-zag fire head a top surface, the major intermediate portion of which is convex and the end portions of which preferably rise towards the free ends of said fire head.

My invention also comprises the novel details of construction and arrangements of parts, which in their preferred embodiments only are illustrated in the accompanying drawings which form a part of this specification, and in which:

Fig. 1 is a plan view of an assembly bar showing individual grate segments assembled

on the ends thereof with the intermediate group of segments omitted.

Fig. 2 is a side elevation of one end of the assembled grate bar shown in Fig. 1.

Fig. 3 is an enlarged cross-sectional view, taken on the line III—III of Fig. 2, showing a support in side elevation.

Similar reference numerals refer to similar parts throughout the drawings.

According to the embodiment illustrated, I show an assembly bar 4, preferably adapted to rock by being provided at each end with an upturned portion 5 bearing a trunnion 6. The assembly bar in cross section is seen more clearly in Fig. 3, and comprises a rounded top portion 7 and a base portion 8 which has its side walls 9 preferably disposed to flare outwardly at a slight angle and which is undercut at 10 to reduce weight by the removal of superfluous metal.

The side faces of the assembly bar are preferably uninterrupted longitudinally thereof, thereby permitting the grate segments to be readily mounted thereon and slid lengthwise therealong until they abut and assume their working position.

The interchangeable grate sections are all alike except that one or more may have cast integral therewith a depending arm 11 adapted to be connected at its lower end to a grate shaking bar, not shown. Except in respect of this arm 11, the grate segments are all duplicates of each other and the description of one therefore will apply to all.

Referring now more particularly to Figs. 2 and 3, the segments are shown to be formed of relatively thin castings, each having a zig-zag shape in horizontal cross section whereby it is provided with angularly disposed vertical sections 12, 13, 14, 15, 16, 17 and 18, which adjoin and form the fire head which is convex over the sections 13 to 17, inclusive, and which rises slightly outwardly over the sections 12 and 18. These sections 12 and 18 are provided on each side face with an offset shoulder 19 having a downwardly tapering bottom edge 20, which shoulders are wide enough to abut, as shown in Fig. 1, when the segments are in assembled position on the bar 4. Each of the segment sections decreases in thickness downwardly so as to have the proper draft and it will be observed that the sections 12 and 18 have their bottom edges slanting upwardly and inwardly, while the sections 13 and 17 have their bottom edges extending down as they approach the sections 14 and 16, respectively, and that the bases of these latter sections extend down further to the bottom of what I term the saddle portion of the segment, which portion is formed almost wholly as a part of the middle section 15.

Referring to the side face of the grate segment as viewed in Fig. 3, this saddle is formed by providing on each face of the section 15 a

shoulder 21 sloping from the point 22 downwardly and outwardly and terminating in a face 23 which is substantially flush with the outer edge of the section 15, except that the latter is flattened out to form the surface 24 which is flush with the surface 23. This flattened surface 24 is interrupted and is continued near the base of the saddle to form the face 25 and similarly the face 23 on its side is interrupted and renewed at the bottom of the saddle to form the face 26. The interruption of these faces leaves a depression indicated in Fig. 3.

The description of the obverse face of Fig. 3 applies equally to the reverse face of this figure when the segment is turned about a vertical axis 180°.

The saddle formed by the enlarged shoultered portions 21 is provided with a recess shaped at its upper end to receive the top edge 7 of the assembly bar and at its bottom to conform to the base portion 8 of the assembly bar except that its side edges are preferably parallel so as to have only a point contact near the base of each side 9 of the bar. Also the saddle recess is enlarged so as to clear the assembly bar except opposite or adjacent to its three points of contact.

It will be observed that the point 22 lies below a horizontal plane indicated at X—Y Fig. 3, which practically bisects the segment, the portion above said plane constituting the fire head and that below the line, the base and saddle portions. The purpose in this construction is to bring below this line all of the saddle and base portion of the segment and to leave above the line only the fire head proper with its end abutments 19. With such a design it will be seen that in casting these segments the patterns may have the top portion above the line X—Y detachable from the base portions so that interchangeable top pattern sections can be used to cast the fire head to adapt it to the furnace where it is to be used without requiring any variation in the standard assembly bar and segment base. This is of material value in reducing the pattern cost by allowing great flexibility in design.

It will be observed that the grate segment section 15, which is at the center of the grate segment, straddles the assembly bar 4, passing over same at an angle and that it is reinforced throughout by the shoulders 21 which extend the full width of this middle panel.

The segments when assembled will have their shoulders 19 and 21 abutting throughout, thus giving them engagement at the center and on each side at their free ends. They provide gradually increasing downward clearance for the escape of ashes and their zig-zag treads as they rock will pass under all of the fire bed, thus leaving no part thereof from which, as the grate rocks, the ashes may not fall freely and be discharged. While the

casting forming the grate segment, except where shouldered, is quite thin, its width from top to bottom is carefully designed to give it ample strength to withstand all normal working stresses.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

What I claim as new, is:—

15. 1. A grate bar segment formed of a thin casting having zig-zag shape in plan with its central section shouldered symmetrically on opposite sides to form a saddle having opposite parallel faces flattened to form vertical 20 abutment surfaces interrupted between their upper and lower portions, the top of the shoulder on each side of the section sloping downwardly and outwardly from its juncture with said section.

25. 2. A grate segment composed of seven thin vertical panels arranged in zig-zag relation as viewed in plan, the panels being of substantially equal width and all downwardly tapered with the five center panels convex 30 overhead and the end panels being of greater length vertically along their free edges than along their inner edges the end and center panels being provided with bosses to abut adjacent grate segments.

35. 3. In a grate of the character embodying an assembly bar and a plurality of grate bar segments straddling the assembly bar, grate bar segments each comprising a firehead and a base, the firehead being zig-zag in plan and 40 being enlarged at its ends to abut adjacent ends of fireheads, and the base being provided with bosses at its sides to abut the bases of adjacent segments, the abutting portions providing for continuous opening from end to 45 end between adjacent fireheads.

In testimony whereof I affix my signature.
CALVIN R. WAID.
